UNITED STATES PATENT OFFICE.

ADAM BLUEGE, OF CHICAGO, ILLINOIS.

BUNDLE OR PACKAGE TYING MACHINE.

1,342,981.

Specification of Letters Patent. Patented June 8, 1920.

Application filed July 21, 1919. Serial No. 312,321.

To all whom it may concern:

Be it known that I, ADAM BLUEGE, a citizen of the United States, residing at Chicago, in the county of Cook and State 5 of Illinois, have invented certain new and useful Improvements in Bundle or Package Tying Machines, of which the following is a specification.

This invention relates to certain improvements in bundle or package tying machines but more particularly to that type of such machines employed for tying or binding with wire, as a tying medium, boxes, cases or containers of varying sizes, different 10 shapes, and of any suitable material.

The principal object of the invention is to provide a machine of the above mentioned general character which shall be simple and inexpensive in construction, 20 strong, durable and highly efficient in operation.

Another object is to provide a machine of this general character of such construction, arrangement and operation of its 25 parts, that the tying medium or wire can be readily disposed around the bundle or package in proper position thereon and so that it can be quickly drawn taut in such a manner that its meeting or overlapping 30 portions may be effectively twisted together or interlocked and then severed.

A further object is to provide adjustable means for supporting the bundle or package to the end that it can be properly positioned on the machine for being tied at 35 suitable points.

Numerous other objects and advantages of the invention will be disclosed in the following description and explanation.

40 The invention consists in certain peculiarities of the construction and in the combination and arrangement of the various parts of the machine whereby certain important advantages are attained and the device is rendered simpler, less expensive and otherwise more convenient and advantageous for use, all as will be hereinafter 45 more fully set forth and specifically claimed.

50 In the accompanying drawings which serve to illustrate an embodiment of the invention,

Figure 1 is a side view of the bundle or package tying machine.

55 Fig. 2 is a front face view thereof showing by dotted lines about the positions the

bundle or package and the tying medium or wire will occupy in the initial steps of tying the package.

Fig. 3 is a plan view of the machine. 60

Fig. 4 is a side view of the upper portion of the machine taken on line 4-4 of Fig. 3, looking in the direction indicated by the arrows showing the means for raising and lowering the twisting or interlocking mechanism for the wire or tying medium and for operating said mechanism. 65

Fig. 5 is a vertical sectional view of said mechanism taken on line 5-5 of Fig. 3 looking in the direction indicated by the 70 arrows.

Fig. 6 is a vertical view partly in section taken on line 6-6 of Fig. 3 looking in the direction indicated by the arrows, and

Fig. 7 is a similar view taken on line 75 7-7 of Fig. 3 as indicated by the arrows.

Corresponding numerals of reference refer to like parts throughout the different views of the drawings.

The main or supporting frame of the machine consists of a flat base 10 and a pair of spaced apart uprights 11 vertically mounted thereon. The rear lower portion of each of the uprights 11 is provided with a vertical rack bar 12 to engage the gears 80 13 which are mounted on a shaft 14 near each of its ends, which shaft is horizontally journaled on a movable platform or table 15 which is interposed between the uprights 11 of the main frame in such a 85 way as to be vertically adjusted with respect to said uprights. This table or platform extends forwardly and rearwardly of the frame uprights 11 as is clearly shown in Figs. 1 and 3 of the drawings and has 90 mounted on its upper surface near its rear end an adjustable gage block or member 16 which is by preference in the form of a box triangular in cross-section and has in its bottom a pair of parallel slots 17 to 100 receive screw bolts 18 seated in the rear portion of the platform 15 and extended upwardly therefrom. Each of the bolts 18 has mounted thereon a thumb nut 19 which can be turned in the proper directions to 105 release or clamp the floor of the gage block or member 16 after it has been adjusted to the proper position. One of the gears 13 on the shaft 14 carries on its inner face and around said shaft a ratchet wheel 20 with

110 which one end of a pawl 21 engages to prevent backward movement of the gears 13

and the shaft 14 on which they are mounted. The pawl 21 is pivoted to one side of the movable platform 15 and has secured to its outer end one end of a spring 22 the other end of which is connected to a projection 23 on said platform. The end of the shaft 14 adjacent the pawl 21 has fixed thereon a handle 24 by means of which the shaft 14 and its gears can be rotated in the proper direction to raise and lower the platform 15 as may be desired.

It will be understood that the pawl 21 can be released from the ratchet wheel 20 by pressing downwardly on its outer portion when it is desired to lower the platform. Extended cross-wise of the uprights 11 and secured thereto at their upper portions is a vertically disposed plate 25 which has on its front face a pair of vertically disposed guides 26 which are L-shaped in cross-section to engage similarly shaped and disposed guide members 27 located on the rear surface of a vertically disposed plate 28 which has on its rear surface at about its middle a vertical rack bar 29 with which a gear 30 mounted on a shaft 31 and extended through an opening 32 in the plate 25, engages.

As shown in Fig. 3 the shaft 31 is journaled in suitable bearings 33 on the rear surface of the plate 25 and extends at one of its ends laterally beyond one of the uprights 11 of the main frame. Fixed to this end of the shaft 31 is an operating lever 35 which extends forwardly with respect to the main 35 or supporting frame and has fulcrumed thereon near its free end a grip lever 36, see Fig. 3, which is connected at its inner end to a locking rod 37 which is longitudinally supported on the lever 35 by means 40 of spaced apart brackets 38 between which is located a spring 39 which surrounds said rod and will actuate it in one direction. The inner end of this rod is adapted to engage notches 40 in a segmental rack 41 secured to 45 the outer surface of the upright 11 adjacent to the lever 35 so as to hold said lever in a fixed position.

The inner end of the spring 39 rests against a collar 42 or similar projection on 50 the rod 37, so that when pressure is removed from the grip lever 36, said rod will be projected inwardly to engage one of the notches 40 in the rack 41 as will be readily understood.

55 The vertically movable plate 28 is provided with three parallel spaced apart and forwardly extended plates 43, 44 and 45, which as shown, are vertically disposed and have transversely journaled thereon a shaft 60 on which is rigidly mounted between the members 44 and 45 a gear 47 and between the members or plates 43 and 44 another gear 48, which is somewhat greater in diameter than the gear 47, as is clearly shown in Figs. 65 2, 3 and 6 of the drawings. A smaller gear

49 is mounted on a shaft 50 transversely journaled on the front portion of the members or plates 43, 44 and 45, which latter gear meshes with the gear 47 as well as with one of the wire twisting or interlocking members, as will be presently explained. 70

Fixed on the shaft 46 near one of its ends is a lever 51 which normally occupies an upright position as shown but which can be moved forwardly in order to turn the gears 75 47 and 48 and thereby operate the wire twisting or interlocking members or elements, each of which is designated as a whole by the reference numerals 52 and 53, and are cylindrical in shape, and transversely journaled in the lower front portions of the members or plates 43, 44 and 45, each of which plates is provided in the lower portion of its front part with a cut-away portion 54 for the reception or guidance of the wire or tying 80 medium.

As is clearly shown in Figs. 5, 6 and 7, each of the wire twisting members 52 and 53 is provided on its periphery with gear teeth 55 to mesh with gears 48 and 49 respectively. 90 It will also be seen and understood by reference to said figures of the drawings that the wire twisting members 52 and 53 are provided with radial slots 56 which register with one another and are also adapted to register 95 with the cut-away portions 54 in the plates 43, 44 and 45 so that the wire or tying medium may be inserted in said slots, it being understood that the slots are open at their outer edges. 100

Each of the members 43, 44 and 45 is provided in its lower front portion with a bearing 57 which is circular except for the cut-out portion 54 and these openings or bearings are for the purpose of receiving the hubs or 105 ends of the cylindrical wire twisting members 52 and 53 as will be readily understood by reference to Fig. 5 of the drawings. The inner end of the twisting member 53 is provided with a socket 58 to receive a cylindrical 110 projection 59 on the inner end of the twisting member 52 which projection fits in said socket in such a way that the members 52 and 53 may have independent movement. As the member 53 is in mesh with the gear 49, 115 which latter gear meshes with the gear 47 while the member 52 is directly in mesh with the gear 48, it is obvious that the members 52 and 53 will be turned in opposite directions when the gears 47 and 48 are rotated through the instrumentality of the lever 51 which lever is provided with a downward extension 60 for the purpose to be presently explained. 120

Horizontally mounted on the outer surface 125 of each of the plates or members 43 and 45 is a guide bracket 61 through each of which is slidably extended a bar 62, each of which is provided at its rear end with a reduced portion 63 around which one end of a coiled 130

spring 64 is mounted. The other end of each of the springs 64 is coiled around and mounted on projections 65 extended forwardly from the movable plate 28. The 5 front end of each of the bars 62 is provided with a cutter or knife 66 which project upwardly across the slots 56 in the wire twisting members, and also across the upper portion of the cut-away parts 54 of 10 the supporting plates or members 43, 44 and 45 for said twisting members. The rear portion of each of the bars 62 is provided with an upwardly extended projection 67 against which projection on one of said bars 15 the extension 60 of the lever 51 will contact when said lever is turned sufficiently in the rotation of the gears 47 and 48 to cause the twisting members 52 and 53 to rotate sufficiently to twist the tying wire together 20 when desired.

Mounted on the shaft 46 on the outer surface of the member or plate 45 is an arm 68 which will contact with the projection 67 of the bar 62 located on the adjacent 25 side of the plate 45. Mounted on the front upper portion of the upright 11 adjacent to the plate 45 is a horizontally and laterally extended bracket 69 which has at its upper portion an overhanging guide 70 which is 30 provided with a T-shaped guide-way 71 to receive the rack bar 72 which is correspondingly shaped at its upper portion to fit in said guide-way. This rack bar is reciprocated by means of a gear 73 which is journaled on the bracket 69 below said bar and meshes therewith.

Mounted on the shaft of the gear 73 is a handle 74 by means of which the gear 73 may be turned in the proper direction to move 40 the rack bar as desired. Mounted on the front surface of the bar 72 near its inner end is a bracket 75 which has a forwardly and horizontally disposed extension or floor 76 on which a portion of the wire or tying 45 medium may rest when it is desired to draw the same so as to cause it to tightly bind the package or bundle. Pivoted on the bracket 75 is a grip lever 77 the lower end of which may be serrated or notched to more 50 securely hold the wire. Secured at one of its ends to the upper end of the grip lever 77 is a spring 78 the other end of which is secured to the bracket 75 and said spring will normally cause the lever 77 to grip the 55 wire as is apparent.

Mounted on the front lower portion of the supporting plate or member 43 and extending laterally therefrom is a bracket 79 which has a forwardly and horizontally 60 extending floor 80 located just below the slots 56 in the twisting members 52 and 53 when said slots are placed in proper position to receive the wire 81 as it is being placed in position around the bundle or 65 package for tying the same.

Pivoted on the bracket 79 is a gripping lever 82, which may be of the same construction as the gripping lever 77 and above referred to. The lever 82 has secured thereto at one of its ends a spring 83 the other 70 end of which is secured to the bracket 79 and is for the purpose of causing the lever 82 to grip the wire 81 when desired.

From the foregoing and by reference to the drawings, it will be readily understood and clearly seen that the operation of 75 the machine is simple and as follows:

Assuming that the parts are in about the positions shown in Fig. 2 of the drawing and that the supporting platform 15 has 80 been adjusted to about the proper height and the gage member 16 has been adjusted to accommodate bundles or packages of a certain size, a wire 81 or the tying medium, which may be of any suitable kind but will 85 be referred to hereinafter as wire, is placed between the gripping lever 82 and the floor 80 of the bracket 79 and then located in the slots 56 of the twisting members 52 and 53 and extended in the form of a loop as 90 shown by dotted lines in Fig. 2, so as to rest on the platform 15 near its front and said wire is again located in the slots of the twisting members and extended between the floor 76 of the bracket 75 and the gripping lever 77 thereon by means of which lever the wire will be firmly held.

A package or bundle 84 is then placed as shown by dotted lines in Fig. 2, so as to rest on the lower portion of the wire 81 and on 100 the platform against the gage member. When thus positioned, the movable plate 28 carrying the supporting members 43, 44 and 45 is lowered by turning the lever 35 downwardly until the lower edges of the said 105 plates rest on the upper surface of the package or bundle 84 in which position said parts will be maintained by reason of the engagement of the locking rod 37 with the notches 40 of the keeper or rack 41 thus 110 firmly holding the package in position. By moving the rack bar 72 outwardly, which can be done by means of the handled gear 73 meshing with said bar, it is obvious that the wire 81 will be drawn through the slots 115 56 of the wire twisting members tightly against the package or bundle when by rotating the twisting members 52 and 53 through the instrumentality of the lever 51 and the connections uniting said members to 120 said lever the wire will be twisted in opposite directions at its overlapping portion or that portion thereof engaged by said twisting members, by reason of the fact that said members will be rotated in opposite directions. The wire can now be cut by a slight movement of the lever 51 which will not cause the extension 60 and the arm 68 to 125 contact with the projections 67 of the cutter carrying bars 62, thus forcing said bars 130

rearwardly and causing their knives or cutters 66 to sever the wire. After this has been done the twisting members will be returned to their normal positions as shown in Fig. 2 by the lever 51 when the movable plate 28 carrying the twisting mechanism can be raised from the package or bundle by turning the lever 35 in the proper direction. Then the rack bar 72 can be turned to about the position shown in Fig. 2 when the machine will be ready to receive another bundle or package and the foregoing operation repeated.

Having thus fully described my invention, 15 what I claim as new and desire to secure by Letters Patent is:—

1. A bundle or package tying machine comprising a vertically adjustable support, 20 a wire twisting mechanism mounted for vertical movement above said support, means to raise and lower said mechanism, and means to operate the same.

2. A bundle or package tying machine comprising a vertically adjustable support, 25 a wire twisting mechanism mounted for vertical movement above said support and including a pair of cylindrical wire twisting members having alined radial slots and mounted for rotation, means to raise and lower said mechanism and means to rotate the wire twisting means thereof in opposite directions.

3. A bundle or package tying machine comprising a vertically adjustable support, 35 a wire twisting mechanism mounted for vertical movement above said support and including a pair of cylindrical wire twisting members having alined radial slots, and mounted for rotation, a reciprocating and 40 spring actuated bar located at the outer end of each of said twisting members and having a cutter extended across the slot thereof, means to raise and lower said mechanism, and means to rotate the twisting members in 45 opposite directions and to move said cutter carrying bars in one direction.

4. In a machine of the character described, the combination with a main frame having spaced apart uprights, of a bundle supporting platform movably mounted between said uprights, means to raise and lower said platform, a wire twisting mechanism mounted for vertical movement between the upper portions of said uprights, said mechanism including a vertically disposed supporting frame, a pair of cylindrical wire twisting members having alined radial slots and journaled on said frame, a shaft horizontally journaled on said frame, gears on said shaft one of which is directly geared to one of the twisting members and the other gear indirectly geared to the other twisting member, and an operating lever fixed to said shaft.

5. In a machine of the character described, 65 the combination with a vertically adjustable

support, of a vertically disposed supporting frame mounted for vertical movement above said support, a pair of wire twisting members having alined radial slots and journaled on the lower front portion of said frame, a shaft horizontally journaled on said frame, gears on said shaft one of which is directly geared to one of the twisting members and the other gear indirectly geared to the other twisting member, an operating lever fixed to said shaft, a bracket having a horizontally disposed floor mounted on said frame near the end of one of the twisting members, a spring actuated wire gripping lever pivoted on said bracket, a horizontally and laterally movable bar mounted near that end of the twisting mechanism carrying frame opposite said lever and having a bracket provided with a horizontally disposed floor, a spring actuated wire gripping lever fulcrumed on said bracket, means to reciprocate said bar, and means to raise and lower the wire twisting mechanism frame.

6. In a machine of the character described, the combination with a main frame having spaced apart uprights, of a bundle supporting frame movably mounted between said uprights, means to raise and lower said platform, a wire twisting mechanism mounted for vertical movement above said platform, said mechanism including a vertically disposed and movable supporting frame, a pair of cylindrical wire twisting members having alined radial slots and journaled on said movable frame, a shaft horizontally journaled on said frame, two gears on said shaft one of which is directly geared to one of the twisting members and the other gear indirectly geared to the other twisting member, an operating lever fixed to said shaft, a slideable and spring actuated bar located at the outer end of each of said twisting members and having a cutter extended across the slot thereof, means to raise and lower the said movable frame, means to rotate the twisting members and to move said cutter carrying bars in one direction, a bracket having a horizontally disposed floor mounted on the movable frame near the end of one of the twisting members, a spring actuated wire gripping lever pivoted on said bracket, a horizontally and laterally movable bar mounted on the main frame near that end of the movable frame opposite said lever and having a bracket provided with a horizontally disposed floor, a spring actuated wire gripping lever fulcrumed on said bracket, and means to reciprocate said bar.

7. In a machine of the character described, the combination with a vertically adjustable support, of a wire twisting mechanism mounted for vertical movement above said support, means to raise and lower said mechanism, means to operate the same, wire gripping means located on one side of said mech-

anism, movable wire gripping means on the opposite side of said mechanism and means to move said last named wire gripping means.

5 8. In a machine of the character described, the combination with a main frame having spaced apart uprights, of a bundle supporting platform movably mounted between said uprights, means to raise and 10 lower the said platform and to maintain it in an adjusted position, said main frame having a vertically disposed plate transversely connecting the upper portions of said uprights and provided on its front 15 surface with guides, said plate having between said guides an opening, a vertically disposed movable frame having on its rear portion means to engage said guides, a vertically disposed rack bar on the rear surface 20 of said movable frame in register with the opening in said plate, a wire twisting mechanism mounted on the movable frame, a shaft horizontally journaled rearwardly of said plate, a gear on said shaft in mesh 25 with said rack bar and a lever on said shaft.

9. In a machine of the character described, a wire twisting mechanism consisting of a vertically disposed and movable frame including a plate provided with 30 spaced apart and forwardly extended plates or supporting members provided in their front lower portions with bearing openings, each of said openings having a cut away portion, a pair of cylindrical wire twisting 35 members located in alignment and journaled in said openings, said members having aligned radial slots, a shaft transversely journaled on the forwardly extending supporting members, a pair of gears mounted 40 on said shaft, one of said gears being directly geared to one of the twisting members, a small gear journaled on said supporting members and interposed between the other gear on said shaft and the other twisting 45 member and in mesh with the same, an operating lever on said shaft, and wire gripping means near the ends of the twisting members.

10. In a machine of the character described, a wire tightening mechanism consisting of a slidably mounted member having near one of its ends a bracket provided with a horizontally disposed floor, a gripping lever pivoted on said bracket and extended at one of its ends toward said floor, a spring connected at one of its ends to that portion of the lever opposite the floor and at its other end to said member and normally holding the lever in gripping position with respect to the floor, and means to move said member back and forth.

11. In a machine of the character described, a wire tightening mechanism con-

sisting of a slidably mounted rack bar having at one of its ends a bracket provided with a horizontally disposed floor, a spring actuated gripping lever pivoted on said bracket, a suitably journaled gear in mesh with said rack bar and a handle on the journal of said gear.

12. In a machine of the character described, a wire tightening machine consisting of a spring actuated gripping lever, a fixed bracket having a horizontally disposed floor, said lever pivoted on said bracket, a member for slidable movement having near one of its ends a bracket provided with a horizontally disposed floor, a spring actuated gripping lever pivoted on said bracket, and means to move said member back and forth.

13. In a machine of the character described, a wire tightening means comprising a fixed bracket having a horizontally disposed floor, a spring actuated gripping lever pivoted to said bracket, a slidably mounted rack bar provided at one of its ends with a bracket having a horizontally disposed floor, a spring actuated gripping lever pivoted to said bracket, a suitably journaled gear in mesh with said rack bar, and a handle on the journal of said gear.

14. In a machine of the character described, a wire cutting mechanism consisting of a slideable bar having a cutter extended transversely therefrom near one of its ends, and a similarly extended projection near its other end, a spring connected to said bar for actuating the same in one direction and pivoted means to contact with said projection and to force said bar against the tension of the spring.

15. In a machine of the character described, the combination with a main frame of a wire twisting mechanism mounted thereon for vertical movement including a pair of aligned independently movable twisting members, said members having aligned radial slots to receive strands of the wire, a shaft journaled near said members, a pair of gears on said shaft one of which gears is directly geared to one of the twisting members and the other gear indirectly geared to the other twisting member, an operating lever fixed to said shaft at one of its ends and having a downward extension, a depending arm on the other end of said shaft, a slidably mounted spring actuated bar located near the outer end of each of the twisting members and each having a cutter extended therefrom across the slots of said members, each of said bars having near its rear end a projection adapted to be engaged by the extension on said lever and by said depending arm.
